(57) CLAIM

The ornamental design for a hat brim template as shown and described.

DESCRIPTION

FIG. 1 is a top perspective view from a left side of a hat brim template;
 FIG. 2 is a front view thereof;

FIG. 3 is a rear view thereof;

FIG. 4 is a left side view thereof;

FIG. 5 is a right side thereof;

FIG. 6 is a top view thereof; and,

FIG. 7 is a bottom view thereof.

The broken lines illustrate portions of the hat brim template that form no part of the claimed design.
